CLAIM

The ornamental design for an electric yogurt machine, as shown and described.

DESCRIPTION

1. Electric yogurt machine
  2. Electric yogurt machine
  3. Jar for yogurt machine (part of yogurt machine)
  4. Jar for yogurt machine (part of yogurt machine)
  5. Pot for yogurt machine (part of yogurt machine)
  6. Filter of pot for yogurt machine (part of yogurt machine)
  7. Filter for yogurt machine (part of yogurt machine)
  8. Pot for yogurt machine (part of yogurt machine)
  9. Pot with lid for yogurt machine (part of yogurt machine)
  10. Yogurt probe (part of yogurt machine)
